UNITED STATES PATENT OFFICE.

AUGUSTIN J. CHEVRETTE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

COMBINED WEFT DETECTING AND TRANSFERRING MECHANISM.

Application filed March 19, 1925. Serial No. 16,749.

This invention relates to weft detecting mechanism of the type shown in prior patent to Ryon No. 1,372,316 of March 21, 1921.

The detector shown in said patent is 5 mounted on the transerrer arm of the replenishing mechanism and the latter is given a periodic downward movement on each alternate beat of the lay to present the detector carried thereby to the yarn in the active 10 shuttle.

In such mechanisms it has been found that the time for operating the detecting mechanism is very short, the detector necessarily entering the top of the shuttle, detecting the 15 yarn, and moving out of the shuttle during the brief interval that the lay is at the extreme forward part of its beat. In the aforesaid patent the device for reciprocating the transerrer arm comprises a cam with a 20 steep point and a cooperating lever and roll but it has been found that the necessary clearance between the roll and the cam causes a loss of motion which permits the transerrer arm and hence the detecting 25 mechanism to remain in lowest position longer than is desired. In order to overcome these disadvantages I have provided resilient means for returning the transerrer from its lowest position as soon as the cam will 30 permit such motion, this mechanism including a spring mounted independently of the transerrer mechanism and having a lost motion connection therewith which permits the transerrer to have a free motion under control of the cam at all times except when said 35 transerrer and detector are near the shuttle.

It is a further object of my invention to provide resilient means supported independently of the transerrer arm and capable of 40 adjustments which in no way affect the operation of the detecting mechanism.

With these and other objects in view which will appear as the description proceeds, my invention resides in the combination and arrangement of parts hereinafter described and set forth in the claims.

In the accompanying drawings wherein I have shown one form of my invention,

Fig. 1 is a central vertical section through 50 a weft replenishing loom of the multi-color type looking in the direction of the detecting mechanism which is associated with my invention,

Fig. 2 is an enlarged end view looking in the direction of arrow 2, Fig. 1, and 55

Fig. 3 is a view looking in the direction of arrow 3, Fig. 2.

Referring to the drawings, loom frame 10 supports a replenishing mechanism 11 of the multi-color type such as set forth in Patent No. 1,030,748 and modified by the changes shown in Patent No. 1,372,316. Pivotedly mounted as at 12 on the replenishing mechanism 11 is a transerrer arm 13 having mounted thereon a detector 14 adapted at indication of weft exhaustion to actuate a pin 15 which cooperates with lever 16 to give the initial indication of weft exhaustion. Pivotedly mounted as at 17 to the transerrer arm 13 is a link 18 the lower end of which is connected as at 19 to lever 20. Said lever 20 is pivotally connected as at 21 to a stand 22 secured to the frame 10 and has mounted on the rearwardly extending arm 23 thereof a roll 24. Said roll is located in a groove 25 of cam 26. Said cam is secured to the bottom shaft 27 and has a point 28 which serves to raise the rear end of the lever when the lay 29 approaches front center on alternate beats. The bottom shaft 27 rotates once for every two picks of the loom and the transerrer arm 13 is therefore given a downward motion every second pick when the shuttle is at the magazine end of the loom. 70 75 80 85

As previously stated it has been found that the detector remains in lowest position longer than is desirable because of the time required to reverse the direction of movement of lever 20 and my invention relates to means to lift the detector as soon as possible after detecting. In order to require the detector to start on its upward movement as soon as possible I provide the transerrer arm with an extension 40 to which is secured a pin or other projection 41. Said pin 41 extends through a slot 42 formed in the lower end of a link 43 the upper end of which is threaded as at 44 to receive nut 45. A boss 46 is formed integral with the replenishing mechanism 11 and has extending therethrough an opening 47 somewhat larger than link 43 to permit the latter to move freely therethrough. The lower end of the link is provided with shoulders 48 against which the lower end of a compression spring 100 105

49 presses. The upper end of spring 49 engages the boss 46 and is constantly under compression to hold the link yieldingly in lower position.

5 The position of the pin 41 with respect to the slot 42 is such that said pin will not engage the upper end of the slot until the transferrer arm 13 has almost reached the lower limit of its travel, at which time said 10 pin 41 will engage link 43 and compress spring 49. As the cam 26 rotates the roll 24 will pass the point 28 and spring 49 will immediately act to raise the transferrer arm 13 without waiting for said roll to be actuated by the cam slot 25. In this way the 15 transferrer is made to start on its upper movement without loss of time and the lay can carry the shuttle S backwardly without having the forward wall of the shuttle 20 engage the lower end of the detector 14. Slot 42 is long enough to permit the transferrer arm to be moved upwardly under action of the cam 26 to actuate the replenishing mechanism as set forth in the afore- 25 said Patent No. 1,372,316, the spring 49 being idle and not affecting the transferrer arm at such times. In order to keep the link 43 in operative relationship with the pin 41 I may employ a washer 50 and cotter 30 pin 51 between which and the arm 40 is located the slotted end of the link 43.

I am aware that Patent No. 1,345,508 issued to Ryon July 6, 1920, shows a spring which may operate to lift the transferrer 35 arm from its lowest position but in this patent the spring actuates the plunger of an air compressor and is necessarily supported entirely by the transferrer arm. Also, adjustments of the spring which are 40 found desirable in the construction set forth herein are not possible in the said patent without affecting the operation of the weft detector.

From the foregoing it will be seen that I 45 have provided a resilient mechanism for starting the transferrer arm on its upward

movement without loss of time, said mechanism being supported independently of the transferrer arm and being capable of adjustments which in no way affect the operation of the detecting mechanism. 50

Having thus described my invention it will be apparent that changes and modifications may be made therein by those skilled in the art without departing from the spirit and 55 scope of the invention, and I do not wish to be limited to the details herein disclosed, but what I claim is:

1. In a weft replenishing loom, a combined 60 weft detecting and transferring mechanism, means to lower and raise said mechanism toward and from the shuttle at regular intervals, resilient mechanism to be operatively connected to the transferrer arm only at such 65 times as the latter is near the lower limit of its travel, and means to support said resilient mechanism independently of and adjustable with respect to the transferrer arm, said resilient mechanism having a lost motion connection with the transferrer arm to disconnect the resilient mechanism from the transferrer arm as the latter approaches the upper 70 limit of its travel.

2. In a weft replenishing loom, a combined 75 weft detecting and transferring mechanism, means to lower and raise said mechanism toward and from the shuttle at regular intervals, resilient mechanism to be operatively connected with the transferrer arm as the latter approaches the lower limit of its travel 80 and as said transferrer arm starts on the upward movement after reaching its lowest limit of travel, said resilient mechanism comprising a link the lower end of which is slotted, a coil spring interposed between the 85 link and the frame of the replenishing mechanism and an element extending from the transferrer arm in the said slot.

In testimony whereof I have hereunto affixed my signature.

AUGUSTIN J. CHEVRETTE.
